UNITED STATES PATENT OFFICE.

BYRON V. SEEVERS, OF OSKALOOSA, IOWA.

DESIGN FOR AN AUTOMOBILE-LAMP.

40,808.

Specification for Design.

Patented Aug. 2, 1910.

Application filed May 25, 1910. Serial No. 563,445. Term of patent 14 years.

To all whom it may concern:

Be it known that I, BYRON V. SEEVERS, a citizen of the United States, residing at Oskaloosa, in the county of Mahaska and State of Iowa, have invented a new, original, and ornamental Design for Automobile-Lamps, of which the following is a specification, reference being had to the accompanying drawing, forming part thereof.

The figure is a perspective view of a lamp showing my new design.

I claim:

The ornamental design for an automobile lamp as shown.

BYRON V. SEEVERS.
